PRESSURE REGULATOR

**Earnest J. Dillman, Detroit, Mich., assignor to
Detroit Lubricator Company, Detroit, Mich., a
corporation of Michigan**

Application March 27, 1944, Serial No. 528,252

3 Claims. (Cl. 50—23)

1

This invention relates to new and useful improvements in refrigerating apparatus and more particularly to means for controlling the loading of the refrigerant medium compressor.

An object of the invention is to provide means to regulate the pressure at which the refrigerant medium is supplied to the compressor so that the quantity of refrigerant medium to be compressed on the compressor working stroke will be maintained within safe limits.

Another object is to provide a novel pressure responsive valve for limiting the back pressure to which the compressor is subjected.

The invention consists in the improved construction and combination of parts to be more fully described hereinafter and the novelty of which will be particularly pointed out and distinctly claimed.

In the accompanying drawings to be taken as a part of this specification, there are fully and clearly illustrated several preferred embodiments of the invention, in which drawings:

Figure 1 is a diagrammatic view of a refrigerating apparatus showing the cooperative relation of the back pressure controlling valve and the compressor;

Fig. 2 is an enlarged detail view in central vertical section of the valve of Fig. 1 and a portion of the compressor, and

Fig. 3 is a view in vertical central section of another form of back pressure controlling valve.

Referring to the drawings by characters of reference, 1 designates generally a compressor driven by an electric motor 2 and here shown as of the reciprocating piston type, although it will be apparent that the invention is equally applicable to rotary compressors. The compressor cylinder 3 has an inlet conduit 4 controlled by a pressure regulating valve 5, shown in detail in Fig. 2. The compressor and its motor and inlet pressure valve are contained within a hermetically sealed housing 6, as is well understood in the art, so that the motor and compressor will be cooled by the expanded refrigerant medium. The compressor cylinder 3 contains the usual reciprocating piston 7 having a spring pressed inlet valve 8. The outlet from the compressor controlled by the usual spring loaded check valve (not shown) discharges through an outlet conduit or pipe 9 which is sealed in and extends through an opening in the wall of the housing 6. The conduit 9 connects to the inlet of a refrigerant medium condenser 10 which may be cooled by a motor driven fan 11. The outlet of the condenser 10 feeds through an expansion device 12, such as the well known cap-

2

illary tube connected to the inlet of an evaporator 13. The outlet of the evaporator is connected by a suction conduit or refrigerant medium return line pipe 14 to the interior of the housing 6, the discharge end of the conduit 14 being hermetically sealed in and through the housing wall, as at 15.

Referring to Fig. 2 the inlet conduit 4, which is a hollow tubular member, is supported and sealed in an opening or aperture 16 through the side wall of the compressor 1 on the inlet or suction side of the piston 7. The valve 5 is supported on the free upper end of the conduit 4 and has a cup-like tubular casing 17 with an outlet opening 18 centrally through its base or bottom wall 19. The upper end of the conduit 4 extends into and is sealed in the opening 18 and to the wall 19, as at 20. Within the casing 17 there is a supporting disc or plate member 21 having a central aperture therethrough and which is supported and sealed at its periphery in an internal annular channel 22 formed in the side wall of the casing 17. The supporting member 21 has a plurality of flow spaces or openings 23 surrounding its central opening for the flow of refrigerant medium to the outlet 18. Supported and sealed in the central aperture of member 21, there is a cup-like end wall member 24 of an expandable contractible pressure responsive member or metal bellows 25. The bellows end wall 24 forms a dash pot housing and has its base positioned adjacent the outlet 18 and has sealed therein a filling tube 26. The end wall 24 is provided with an external shoulder which seats on the member 21 and forms an internal shoulder to receive the marginal edge portion and thereby support a spring supporting disc and stop member 27. The bellows member 25 has one end hermetically sealed as at 28 to the out-turned flange or rim of the end wall 24 and has its other end hermetically sealed as at 29 to a head or end wall plate member 30. Secured in and through a central aperture in the head member 30 there is a valve stem 31 which extends centrally within the bellows member 25 and through an aperture in the stop member 27 and terminates within the cylindrical portion of the end wall 24 positioned beneath the stop member 27. This cylindrical end wall portion provides a dash pot chamber 32 having a piston 33 secured on the inner end of the stem 31 and engageable with the stop member 27 to limit outward movement of the stem 31. Within the bellows member 25 and surrounding the stem 31 there is a helical coil spring 34 which is held

under compression between the bellows head member 30 and the stop member 27 and which normally tends to hold the bellows member 25 expanded to the extent permitted by engagement of the piston 33 with the stop member 27. The bellows member 25 is evacuated of air through the filling tube 26 and is then charged therethrough with an inert gas and also with a liquid such as oil, say to the line L-L, to fill the dash pot chamber 32, after which the tube 26 is hermetically sealed. The pressure of the gas within the bellows member 25 and the force exerted by the spring 32 together hold the bellows member expanded with a predetermined force which may be say 15 lbs. per square inch absolute. Surrounding the outer end portion 35 of the stem 31 there is a valve plate member 36 having its marginal edge portion secured and sealed in an internal annular channel 37 in the wall of the casing 17. The stem portion 35 extends through a valve port 38 centrally positioned in and through the plate member 36. Cooperable with the port 38 there is a valve member 39 which is screw-threaded on the stem portion 35 for adjustment and which is positioned on the inlet side of the valve port. The inlet or open end of the casing 17 is provided with a strainer 40, preferably layers of wire screen mesh of graduated fineness which are supported by an annular plate 41 seated on an annular internal shoulder 42 in the casing 17. The strainer 40 is locked and held in position against the plate 41 by a resilient bezel ring 43.

The operation of the refrigerating apparatus and compressor with the valve of Fig. 2 is as follows: When the motor 2 and fan 11 are started in operation for the beginning of a refrigerating cycle, the pressure in the casing 17 and acting externally on the bellows member 25, will be in excess of the internal force on the bellows head member 30 so that the valve member 39 will be closing its port 38. The compressor operation will quickly reduce the pressure in the casing 17, so that the pressure of the gas and the force of the spring 34 will move the valve member 39 toward open position, thereby admitting refrigerant medium through the port 38 for supply to the compressor. The pressure of the refrigerant medium on the outlet side of the port 38 and around the bellows member 25 will accordingly be held substantially constant, and tendency of the valve member 39 to chatter or vibrate, due to the reciprocations of the compressor piston, will be smoothed out by the action of the dash pot 32. When the motor 2 is stopped upon the occurrence of the desired low evaporator temperature or temperature in the space to be cooled, the pressure of the refrigerant medium in the housing and therefore in the valve casing 17 will increase, thereby moving the valve member 39 toward closing position and when the pressure in the casing 17 and on the suction side of the compressor 1 exceeds the force exerted by the pressure responsive bellows member 25, then the valve member 39 will be seated and close the port 38 so that the compressor back pressure cannot exceed the pressure for which the valve 5 is set.

Referring to Fig. 3, the tubular conduit member 4, for connection to the compressor inlet, carries a cup-like casing 50 at its upper or inlet end. The casing 50 has a side wall outlet 51 which is sealed to the end of the conduit member 4. Within the casing 50 there is a pressure responsive expandable collapsible member 52,

preferably a metal bellows, having head or end wall members 53, 54 having their marginal edge portions hermetically sealed to the ends of the bellows member. The end wall member 54 has a tubular supporting fitting 55 which is externally screw-threaded to be received in and through a nut 56 secured and sealed in a central aperture through the bottom wall 57 of the casing 50. The fitting 55 is provided with an internal tube 58 through which the bellows member 52 may be evacuated of air so that temperature change will not vary the internal pressure of the member 52. The tube 58 is hermetically sealed, as at 59, after the bellows member 52 has been evacuated of air. Supported and sealed in a central aperture through the head member 53 there is a valve supporting member 60 having an internally screw-threaded socket to receive one end of a valve stem 61. The member 60 is provided within the bellows member 52 with a head 62 forming a stop member cooperable with a stop member 63 rigid with the head member 54. The stop members 62, 63 cooperate to limit the expansion of the bellows member 52 under the force of a helical coil compression spring 64 which surrounds these members and is held under compression between the head members 53, 54. The spring 64 exerts a predetermined expansible force which determines the maximum pressure of the refrigerant medium within the casing 50, and therefore the compressor back pressure. The valve stem 61 extends through a valve port 65 in a valve plate member 66 which is secured and sealed at its periphery to the rim or open end portion of the casing 50, as at 67. The stem 61 carries a valve member 68 positioned on the opposite side of the plate member 66 from the bellows member 52 so that it is movable toward closed position upon collapse or contraction of the bellows member 52. The operation of this valve and its control of the compressor back pressure will be clear from the foregoing description of the apparatus of Fig. 1 and the valve of Fig. 2.

What is claimed and is desired to be secured by Letters Patent of the United States is:

1. A pressure limiting valve for controlling the inlet pressure to a compressor, comprising a cup-like casing having an outlet aperture through its end wall, a transverse supporting member in said casing and having a central aperture surrounded by flow ports, a cup-like bellows end wall member forming a dash pot housing and extending through and secured in said central aperture and having its base adjacent said outlet aperture, a metal bellows member having one end sealed to the rim of said wall member, a head plate member having its periphery sealed to the other end of said bellows member and having a central opening, a valve port plate member extending across said casing in spaced relation to said head plate member and having a central valve port, a valve stem secured and sealed in said head plate member central opening and having one end extending through said valve port and having its other end extending into said dash pot housing, a valve member secured on said one stem end and operable to close said valve port upon contraction of said bellows member, a piston in said dash pot and secured to said other stem end, liquid in said dash pot, a stop plate member in said casing and having an aperture for passage of said stem therethrough, a helical coil spring in said casing and surrounding said stem, said spring being held

under compression between said stop plate member and said head plate member, said piston being engageable with said stop plate member to limit expansion of said bellows member by said spring.

2. A pressure limiting valve for controlling the inlet pressure to a compressor, comprising a cup-like casing having an outlet aperture through its end wall, a transverse supporting member in said casing and having a central aperture and a flow port therethrough, a cup-like bellows end wall member forming a dash pot housing and extending through and secured in said central aperture and having its base adjacent said outlet aperture, a metal bellows member having one end sealed to the rim of said wall member, a head plate member having its periphery sealed to the other end of said bellows member and having a central opening, a valve port plate member extending across said casing in spaced relation to said head plate member and having a central valve port, a valve stem secured and sealed in said head plate member central opening and having one end extending through said valve port and having its other end extending into said dash pot housing, a valve member secured on said one stem end and operable to close said valve port upon contraction of said bellows member, a piston in said dash pot and secured to said other stem end, a stop plate member in said casing and having an aperture for passage of said stem therethrough, a helical coil spring in said casing and surrounding said stem, said spring being held under compression between said stop plate member and said head plate member, said piston being engageable with said stop plate member to limit expansion of said bellows member by said spring.

3. A pressure limiting valve for controlling the inlet pressure to a compressor, comprising a cup-like casing having an outlet aperture, a transverse supporting member in said casing and having a central aperture, a cup-like bellows end wall member forming a dash pot housing and extending through and secured in said central aperture, a metal bellows member having one end sealed to the rim of said wall member, a head plate member having its periphery sealed

to the other end of said bellows member, a valve port plate member extending across said casing in spaced relation to said head plate member and having a central valve port, a valve stem secured to said head plate member and having one end extending through said valve port, a valve member secured on said one stem end and operable to close said valve port upon contraction of said bellows member, a piston supporting stem secured to said head plate member and extending into said dash pot, a piston in said dash pot and secured to said piston supporting stem, a stop plate member in said casing and having an aperture for passage of said piston supporting stem therethrough, and a helical coil spring in said casing and surrounding said piston supporting stem, said spring being held under compression between said stop plate member and said head plate member, said piston being engageable with said stop plate member to limit expansion of said bellows member by said spring.
